UNITED STATES PATENT OFFICE.

JAMES SCRIPPS BOOTH, OF DETROIT, MICHIGAN.

DESIGN FOR A RADIATOR.

44,233.

Specification for Design.

Patented June 24, 1913.

Application filed February 13, 1913. Serial No. 748,248. Term of patent 14 years.

To all whom it may concern:

Be it known that I, JAMES SCRIPPS BOOTH, a citizen of the United States of America, residing at Detroit, in the county of Wayne and State of Michigan, have invented a new, original, and ornamental Design for Radiators, of which the following is a specification, reference being had therein to the accompanying drawing, forming part thereof.

Figure 1 is a side elevation of a radiator showing my new design; Fig. 2, an end elevation of the same; and Fig. 3, a plan view.

I claim:

The ornamental design for a radiator as shown.

In testimony whereof I affix my signature in presence of two witnesses.

JAMES SCRIPPS BOOTH.

Witnesses:

ANNA M. DORR,
LEWIS E. FLANDERS.
